UNITED STATES PATENT OFFICE.

JOHN H. ROCK, OF BRIDGEPORT, CONNECTICUT, ASSIGNOR TO THE HOLMES & EDWARDS SILVER COMPANY, OF SAME PLACE.

DESIGN FOR A HANDLE FOR SPOONS, &c.

SPECIFICATION forming part of Design No. 23,108, dated March 13, 1894.

Application filed December 11, 1893. Serial No. 493,409. Term of patent 14 years.

To all whom it may concern:

Be it known that I, JOHN H. ROCK, a citizen of the United States, residing at Bridgeport, in the county of Fairfield and State of Connecticut, have invented and produced a new and original Design for Spoons, Forks, and Similar Articles; and I do declare the following to be a full, clear, and exact description of the same, reference being had to the accompanying drawings, forming a part thereof.

Figure 1 is a plan view of the upper or obverse side of a spoon embodying my novel design, the embodiment of said design in a fork being indicated by dotted lines, and Fig. 2 is a plan view of the back or reverse side of a spoon embodying my novel design, the embodiment thereof in a fork being indicated by dotted lines.

The leading features of the design consist of an irregular curved outline on both sides of the handle the sides of the handle however, not corresponding with each other in outline

and a plain center at the widest portion of the handle, which is encircled by conventional rococo ornamentation.

25

1 denotes the center, which is plain, and may be either flat or rounded, 2 denotes conventional ornamental waves of so called rococo style, and 3 denotes outwardly curved ornamentation at the apex of the handle. At 30 the base of the handle on the obverse side I provide other ornamentation, as at 4, of the same general character as the rococo waves on the widest portion of the handle.

35

What I claim is—
The design for a handle for spoons, forks and similar articles substantially as shown and described.

In testimony whereof I affix my signature in presence of two witnesses.

JOHN H. ROCK.

Witnesses:

JOHN CUMMINGS,
HENRY G. FOOTE.
